DESIGN FOR A DOLL

Hal Willard Groshong and Edith Blanche
Groshong, Cummings, Calif.

Application January 5, 1938, Serial No. 74,096

Term of patent 7 years

To all whom it may concern:

Be it known that we, Hal Willard Groshong and Edith Blanche Groshong, citizens of the United States of America, residing at Cummings, in the county of Mendocino and State of California, have invented a new, original, and ornamental Design for a Doll, of which the following is a specification, reference being had to the accompanying drawing, forming a part thereof.

Fig. 1 is a front view of a doll, showing our new design; and

Fig. 2 is a rear view thereof.

We claim:—

The ornamental design for a doll substantially as shown.

HAL WILLARD GROSHONG.
EDITH BLANCHE GROSHONG.
